ELECTRIC PHONOGRAPH

Leland D. Norton, Bridgeport, and Lucius P. Petruschell, Stratford, Conn., assignors to Dictaphone Corporation, New York, N. Y., a corporation of New York

Application December 21, 1939, Serial No. 310,368

9 Claims. (Cl. 179—100.4)

This invention relates to electric phonographs and more particularly to electric remote control and power supply arrangement for such phonographs.

5 It is an object of this invention to provide an improved electric phonograph system and an arrangement for supplying electrical power to and remotely controlling the operation of such a phonograph.

10 It is a further object of this invention to provide a power supply system for electric phonographs adapted to supply all of the elements of the electric phonograph circuit with electrical power at proper voltage, whether the phonograph be connected to a 110-volt or a 220-volt power supply line, without the need for altering the electrical characteristic of the phonograph circuit elements.

15 It is also an object of this invention to provide such a power supply system in which a single fuse of low rating is so connected as to protect all of the circuit elements from damage due to overload, whether the system be connected to a 110-volt or a 220-volt power supply circuit.

20 It should be noted that when reference is made herein to 110-volt or 220-volt power supply circuits, these figures are merely used for convenience in terminology, without intent to limit this invention to use with systems of these voltages only, inasmuch as this invention is equally applicable to use on power supply systems of voltages considerably different from these voltages but bearing approximately the same relationship to each other.

25 These and other apparent objects and advantages of this invention are obtained by the means described in the following specification and may be more readily understood by reference to the accompanying drawing which shows a schematic 30 wiring diagram of an electric phonograph power supply and control system embodying the invention.

35 Certain features of invention disclosed in this application are not claimed herein, but are described and claimed in a co-pending application, Serial No. 348,768, filed on July 31, 1940, the latter being a continuation-in-part of the present application.

40 While this invention is applicable to any electrical system having a plurality of individual units requiring electrical power at predetermined voltages for satisfactory operation, for the purposes of the present description it has been shown embodied in a multiple mandrel sound 45 recording machine such, for example, as that

shown in United States Patent No. 2,026,398. Such machines are well-known in the art and do not, per se, form any portion of the invention herein described. It is sufficient for the present description to state that such a machine comprises essentially a plurality of recording units, generally shown at I and II, each having a record supporting mandrel, 2 and 3, rotatably mounted on suitable frames 4 and adapted to be rotated by 110-volt driving motors 6 and 7 through suitable pulleys 8 and 10 and belts 12. The motors 6 and 7 are connected through a single-pole double-throw switch 13 such, for example, as a mercury switch, to a suitable 110-volt power source in the manner hereinafter to be described, 5 so that either motor 6, motor 7, or both motors may be operated by tilting the mercury switch 13, respectively, to the left (as shown in the drawing), to the right, or maintaining it in a horizontal position. Suitable recording units or 10 cutting heads 14 and 15, such, for example, as those shown in United States Patent No. 2,057,621, are associated with each of the mandrels 2 and 3, respectively, and are adapted to cut sound tracks in cylindrical record blanks when such 15 blanks are placed on these record supporting mandrels 2 and 3. These cutting heads 14 and 15 are mounted on suitable carriage structures 20 (not shown) which are adapted to be driven across mandrels 2 and 3 from left to right by 25 means of feed screws (not shown) operated through suitable gears (not shown) from the pulleys 10. Recorder units 14 and 15 are connected to the output of a vacuum tube amplifier 20, through a single-pole double-throw switch 16, 30 which may be similar to switch 13. The input 22 of amplifier 20 is shown connected to a microphone 24, although it may be connected to any electrical source modulated by the sound to be recorded. The amplifier 20 may be any suitable 35 amplifying device having sufficient amplifying ability and power output for the particular installation and it preferably includes a power supply rectifier and filter arrangement. Alternating current power is furnished to the anode 40 potential portion of this amplifier unit through leads 26 from a secondary winding 28 of a power supply transformer, generally indicated at 30, in the manner hereinafter to be described, and the heating current for the filaments or heaters of 45 the vacuum tubes of the amplifier unit 20 is supplied through leads 25 from another secondary winding 32 of the transformer 30.

50 When alternating current power is supplied to amplifier 20 and to the circuit of motors 6 55

and 7, record blanks are placed on mandrels 2 and 3 and the cuttings heads 14 and 15 are placed in their initial or left-hand positions, the apparatus is ready to operate. As described in the above-mentioned United States Patent No. 2,026,398, mercury switches 13 and 16 are pivotally mounted in a linkage system so arranged that when mercury switches 13 and 16 are tilted to the left, as shown in the drawing, motor 6 and recorder 14 are connected, respectively, to the power supply and the output of the amplifier 20. With mercury switches 13 and 16 in this position, motor 6 will operate to rotate mandrel 2 and its associated record blank; and recording head 14, being connected through switch 16 to the output of amplifier 20, will record a sound track on this record blank corresponding to the sound impressed on microphone 24. When recorder 14 almost reaches the end of its path of travel along the record blank on mandrel 2, switches 13 and 16 are tilted until they assume a horizontal position. This connects motor 7 of machine II to the power supply in parallel with motor 6 and starts it operating to rotate mandrel 3 and its associated record blank. At the same time, recorder 15 is connected in parallel with recorder 14 across the output of amplifier 20 and starts traversing the record blank on mandrel 3 to start the recording thereon before the recording on mandrel 2 is ended, thus providing a slight overlap in the recording being made on these two blanks. As recorder 14 progresses further along the record blank on mandrel 2 to the end of the travel, it further actuates the linkage mechanism associated with mercury switches 13 and 16 to tilt them to the right, thus disconnecting motor 6 from the power supply and recorder 14 from the output 18 of the amplifier 20, thereby ending the recording on mandrel 2 of machine I. If the recorded blank on mandrel 2 is replaced by a fresh blank and recorder 14 is moved to its initial position at the left-hand end of mandrel 2, the sequence of operation just described will be repeated in a reverse direction, with mercury switches 13 and 16 being tilted first to horizontal position and then to a left-hand tilted position as recorder head 15 approaches the end of its travel, thus providing a slight overlap in recording on the end of the record blank on mandrel 3 and the start of the record blank on mandrel 2. With this arrangement, by constantly supplying fresh record blanks to the mandrels 2 and 3 as each precedent blank is filled with a sound groove, a continuous recording can be made of any sound impinging on microphone 24. The apparatus thus far described is substantially the same as that disclosed in the above-mentioned United States Patent No. 2,026,398.

Apparatus of this type is frequently used for recording lengthy conferences, conventions, speeches, telephone conversations, etc., and it is therefore frequently desirable to have the microphone at some distance from the recording machine and to provide means for remotely controlling the operation of the machine at the microphone. Such an arrangement also permits the attendant who changes the records on the mandrels 2 and 3 to be in another room remote from the microphone.

In the embodiment shown in the drawing, such remote control is effected by providing a remote control box, generally indicated at 34, connected by a seven-wire cable, generally indicated at 75 36, to the rest of the apparatus. The control

box 34 is provided with a main power supply or "standby" switch 38 for connecting the machine to the power supply circuit to put it in condition for operation; and an operating or "start and stop" switch 40, which is operated by the dictator or speaker whenever he wishes to start or stop the recording action of the apparatus. The control box 34 is also equipped with three suitable indicator lights 42, 44, and 46. Light 42 is a "standby" lamp which lights whenever "standby" switch 38 is closed to indicate that the apparatus is ready to operate. Lights 44 and 46 are connected, respectively, with recording machines I and II to indicate when either of these machines is in operation, i. e., when the recorder heads 14 and 15 are away from their initial or left-hand positions. Indicating lights 48 and 50 are provided at the recording machines I and II to inform the attendant of the condition of the apparatus, light 50 indicating that the apparatus is in "standby" condition, and light 48 indicating to the attendant that the motor circuit either to motor 6 or 7 is closed and therefore that either machine I or II is actually operating. Further, a relay, generally indicated at 52, is provided to close the plate circuits of the amplifier 20 and to close the circuit to motors 6 and 7 whenever the operating switch 40 is in "start" or operating position, and to open these circuits whenever the operator wishes to stop recording.

Indicating lamps 44 and 46 are operated by switches mounted on machines I and II and shown diagrammatically in the drawing at 54 and 56, respectively. These switches 54 and 56 are comprised essentially of lever arms 58 pivoted on the frames 4 to position contacts 60 and 62 to make or break electrical circuits through indicating lamps 44 and 46. Springs 64 hold these contacts in normally closed position. The upper ends of levers 58 are positioned so as to be moved by the recorder units 14 and 15 when they are moved to their initial or extreme left-hand positions (as illustrated by the position of recorder unit 15 in the drawing) to open the circuits between contacts 60 and 62, thus breaking the circuits to the indicating lamps 44 and 46.

If such an instrument is always to be operated in the same place on a fixed power supply line voltage, all of the various elements of the system, i. e., the motors 6 and 7, the attendant "motor operating" indicating light 48, the "ready-to-operate" or "standby" lights 50 and 42, the individual mandrel "operating" lights 44 and 46, the primary of the amplifier power supply transformer 30, and the solenoid of the relay 52, would be connected in parallel across the power supply line in series with a fuse. This is not always the case, however. Recorders of this type frequently must be carried from place to place and are often made up in portable form for this purpose. Such portability requires adaptability to operation on any conveniently available source of electric power. Under these conditions, operation on power supply lines with widely different line voltages is frequently necessary. There is considerable use of both 110 volts and 220 volts as standard line voltage. In order to provide satisfactory portable apparatus of this nature, it is desirable, therefore, that such apparatus be adaptable to operation on 110-volt or 220-volt power supply lines with a minimum of alteration in circuits and circuit elements.

In accordance with this invention, this is accomplished by connecting all of the circuit ele- 75

ments of the electric phonograph in the manner shown in the drawing. Power supply transformer 30 is provided with two electrically equivalent windings 66 and 68. These windings are so designed that when either is connected across 110-volt power supply as a primary winding the plate supply secondary winding 28 and the filament supply secondary winding 32 develop the correct voltages required by the amplifier 20 for satisfactory operation. These two windings 66 and 68 are connected in series through a fuse 70. One end of winding 66 is connected through main power supply switch 38 to one side of the plug 72 adapted to be connected to the available power supply outlet. The other terminal of the power supply plug 72 is connected through a single-pole double-throw switch 74 to one end or the other of the other primary winding 68, depending upon whether the machine is to be connected to a 110-volt or 220-volt power supply.

With this arrangement, when 110-volt operation is desired, the arm of switch 74 is moved to contact 76, thus connecting winding 66 in series with fuse 70 across the 110-volt supply line to act as the primary of the transformer 30. Winding 68 thus becomes an effective secondary winding. For 220-volt operation the arm of switch 74 is placed on contact 78, thus connecting windings 66 and 68 in series, with the fuse 70 connected therebetween, to effectively form a single 220-volt primary winding for connection to a 220-volt power supply. In either case, with the switch 74 properly positioned, dependent upon the voltage of the power supply to which terminal plug 72 is connected, the secondary windings 28 and 32 of the transformer 30 will develop the voltage necessary for proper operation of amplifier 20, and in both cases these secondary windings will be protected by the fuse 70 from overload.

Solenoid 80 of relay 52 is connected in series with "start and stop" switch 40 across primary winding 66. When this solenoid is energized by the closing of switch 40, it closes two pairs of contacts 82 and 84.

Contacts 82 are connected in series with a circuit including motors 6 and 7, mercury switch 13, "motor operating" light 48, and with fuse 70 across primary winding 66. Thus contacts 82, operating in response to energization and de-energization of solenoid 80 caused by closing and opening "start and stop" switch 40, control the starting and stopping of motor 6 or 7, depending upon the position of mercury switch 13, and the operation of signal light 48. It is readily apparent that, when the apparatus is conditioned for operation on 110 volts by moving switch 74 to contact 76, motors 6 and 7 and control light 48 which are 110 volt operated elements, are connected directly across the 110-volt line. When the apparatus is conditioned for operating on 220 volts by moving the contact arm of switch 74 to contact 78, these 110-volt elements are connected across winding 66 which then acts as the secondary portion of a 220-volt auto-transformer, formed by windings 66 and 68 connected in series, to supply them with 110-volt power.

Contacts 84 of relay 52 are connected in series with the plate supply secondary winding 28 of transformer 30 and the plate supply terminals 26 of amplifier 20. Thus, when relay solenoid 80 is deenergized by moving "start and stop" switch 40 to open position to stop operation of motors 6 and 7, the plate circuit of amplifier 20 is opened, thus rendering it inoperative and pro-

longing the life of the electronic tubes in the amplifier.

The 110-volt "ready-to-operate" or "standby" signal lamp 42 in the remote control box 34, and the corresponding lamp 50 mounted at the machine, are connected in parallel across winding 68. On 110-volt operation this winding 68 acts as a 110-volt secondary winding coupled to the primary winding 66 and provides 110 volts for operating these signal lamps whenever the primary 66 is energized, to indicate that the machine is in "standby" condition. On 220-volt operation, when winding 68 acts as one-half of the primary winding of the transformer, the signal lamps 42 and 50 are operated by the 110 volts developed across this winding acting as a secondary portion of an auto-transformer, and similarly indicate that the machine is in "standby" condition.

The 110-volt signal lamps 44 and 46 in the remote control box 34, which indicate which of the two recording heads 14 or 15 is in operation, are connected in series with their respective switch 58 and 56 across winding 66 and fuse 70. Thus, these lamps are connected in parallel with the motors 6 and 7 and the motor "operating" signal lamp 48, so that, as above-mentioned, they are connected directly across the 110-volt line when the apparatus is conditioned for 110-volt operation, and across winding 66 acting as the 110-volt secondary of an auto-transformer when the apparatus is conditioned for operation on 220 volts.

Summarizing the above description, when the apparatus is conditioned for operation on 110 volts, winding 66 acts as a primary winding, winding 28 acts as a secondary winding to deliver plate voltage to amplifier 20, winding 32 acts as a secondary to deliver filaments or heater voltage to amplifier 20, and winding 68 acts as a secondary to deliver 110 volts to signal lamps 50 and 42. In addition, motors 6 or 7, indicating lamps 44, 46, and 48, and solenoid coil 80 are connected directly across the 110-volt power supply. When the apparatus is conditioned for 220-volt operation, windings 66 and 68 are connected in series through fuse 70 and act as a primary winding, windings 28 and 32 still act as secondary windings delivering the same voltage as under 110-volt operation to the plates and filaments of amplifier 20 because the primary still develops the same number of ampere-turns as before. Winding 66 acts as the secondary winding of an auto-transformer to deliver 110 volts to solenoid 80, indicator lamps 44, 46, and 48, and motors 6 or 7; and winding 68 acts as the secondary of an auto-transformer to deliver 110 volts to signal lamps 42 and 50.

Therefore, it is evident that with the apparatus connected as above described, although the electric phonograph circuit is composed of a plurality of circuit elements each requiring a 110-volt power supply for proper operation, it is capable of operating on either 110-volt or 220-volt power supply lines without altering the electrical characteristics of any of the circuit elements by merely moving the arm of single-pole double-throw switch 74 from contact switch 76 to contact 78.

Furthermore, with a machine embodying the invention as above described, the circuit arrangement is such that with the single fuse 70 connected between the windings 66 and 68 it can be used to protect all of the elements of the system against damage whether the machine be condi-

tioned for 110- or 220-volt operation. For example, on 110-volt operation the loads on the fuse 70 are secondary 28 and 32, relay solenoid 80, and winding 68 acting as a secondary. Under 5 these conditions, motors 6, 7, and signal lamps 44, 46, and 48 are not fused. However, if the machine is subjected to a voltage sufficient to cause the fuse 70 to blow, these circuit elements will be protected because the relay solenoid is 10 fused and will be instantly deenergized, thus opening the circuit to these elements. When the apparatus is connected for 220-volt operation, the current through the fuse due to the load on 15 secondaries 28, 32 and windings 66 and 68 acting as auto-transformer secondaries, is considerably decreased, and therefore, although the circuits of motors 6 or 7 and signal lamps 44, 46, and 48 are now connected in the fuse circuit, the normal operating current through the fuse is still maintained 20 at a sufficiently low value so that the fuse used on 110-volt operation is still adequate to protect the circuit elements for 220-volt operation.

I claim:

25 1. An electric phonograph power supply for supplying power to a plurality of load elements of an electric phonograph each of which requires power at a certain predetermined voltage for satisfactory operation, comprising, in combination, 30 a transformer having a first and second winding, said first winding being adapted to be connected across an electrical power source of a first predetermined voltage as a primary winding and serving as a secondary to supply electrical power 35 to certain of said load elements at said first predetermined voltage, said second winding serving as a secondary to said first winding to supply the remainder of said load elements with electrical power at a second predetermined voltage, means 40 for connecting said first and second windings to form a primary adapted to be connected across a power source having a voltage equal to the sum of said first and second predetermined voltages, said first and second windings also serving as 45 secondary windings to supply power to said load elements at said first and second predetermined voltages respectively whereby all of said load elements are supplied with power at said predetermined voltages whether said phonograph is supplied 50 with power at said first predetermined voltage or at a voltage equal to the sum of said first and second predetermined voltage.

2. An electrical phonograph power supply for supplying power to a plurality of load elements 55 of an electric phonograph each of which requires power at a predetermined voltage for satisfactory operation, comprising, in combination, a transformer having a first and second winding, said first winding being adapted to be connected 60 across an electrical power source of said predetermined voltage as a primary winding and serving as a secondary to supply electrical power to certain of said load elements at said predetermined voltage, said second winding serving as a 65 secondary to said first winding to supply the remainder of said load elements with electrical power at said predetermined voltage, means for connecting said first and second windings to form a primary adapted to be connected across a power source having a voltage approximately double said predetermined voltage, said first and second windings also serving as secondary windings to supply power to said load elements at said predetermined voltage whereby all of said load elements are supplied with power at said predetermined voltage or at said substantially greater 70 voltage.

75 3. An electric phonograph power supply for

determined voltage whether said phonograph is supplied with power at said predetermined voltage or at a voltage equal to approximately double said predetermined voltage.

3. An electrical phonograph power supply for 5 supplying power to an electric phonograph circuit including a plurality of load elements requiring power at a voltage of approximately 110 volts for satisfactory operation, comprising, in combination, a transformer having a first 110-volt primary winding and a second 110-volt primary winding, said windings being connected in series, power supply terminals, means for connecting said terminals across first primary winding when said phonograph is to be operated from a 15 110-volt power supply and for connecting said terminals across both of said primary windings in series when said system is to be operated from a 220-volt power supply, certain of 110-volt load elements being connected across said first primary winding, the remainder of said 110-volt load elements being connected across said second primary winding whereby all of said load elements are supplied with power at 110 volts whether said phonograph is connected to a 110- 25 volt or a 220-volt power supply.

4. In an electric phonograph adapted to be operated on 110-volt or 220-volt power supply circuits and having all of its load elements adapted to operate on 110 volts, a power supply, comprising, in combination, a power transformer having a first 110-volt primary winding and a second 110-volt primary winding, said first and second primary windings being connected in series, power supply terminals, means for connecting 30 said power supply terminals across first primary winding to adapt said system for 110-volt operation and across both of said primary windings connected in series to adapt said system for operation on 220 volts whereby all of the 110- 40 volt operated load elements of said phonograph are supplied with power at the proper voltage whether said phonograph is connected to a 110-volt or a 220-volt power supply.

5. An electric phonograph power supply for 45 supplying power to a plurality of load elements of an electric phonograph circuit each of which requires power at a predetermined voltage for satisfactory operation, comprising, in combination, a transformer having a first and second 50 winding, said first winding being adapted to be connected across an electrical power source of said predetermined voltage as a primary winding and serving as a secondary to supply electrical power to certain of said load elements at said 55 predetermined voltage, said second winding serving as a secondary to said first winding to supply the remainder of said load elements with electrical power at said predetermined voltage, means for connecting said first and second windings to form a primary adapted to be connected across a power source having a voltage substantially greater than said predetermined voltage, said first and second windings also serving as secondary windings to supply power to said load 60 elements at said predetermined voltage whereby all of said load elements are supplied with power at said predetermined voltage whether said phonograph is supplied with power at said predetermined voltage or at said substantially greater 65 voltage.

6. An electric phonograph power supply for supplying power to a plurality of load elements of an electric phonograph circuit each of which requires electric power at a predetermined volt- 75

- age for satisfactory operation, comprising, in combination, a transformer having a first and second winding, said first winding being adapted to be connected across an electrical power source 5 of a first predetermined voltage as a primary winding and serving as a secondary to supply electrical power to certain of said load elements at said first predetermined voltage, said second winding serving as a secondary to said first winding 10 to supply the remainder of said load elements with electrical power at a second predetermined voltage, means for connecting said first and second windings to form a primary adapted to be connected across a power source having a voltage 15 substantially greater than said first predetermined voltage, said first and second windings also serving as secondary windings to supply power to certain of said load elements at said first and second predetermined voltages, respectively, 20 whereby all of said load elements are supplied with power at said predetermined voltages whether said phonograph is supplied with power at said first predetermined voltage or at said substantially greater voltage.
- 25 7. An electric phonograph power supply for supplying power to a plurality of circuit elements of an electric phonograph, comprising, in combination, a transformer having a first and second winding, said windings being adapted to be connected across an electrical power source to act as primaries and being adapted to serve as secondaries with respect to each other to supply electrical power to certain of said circuit elements connected across each of said windings respectively, 30 fuse means, said fuse means being connected in series between said first and second windings, means connecting one side of said power supply line with one end of said first winding, and means for connecting the other side of said power supply line to either end of said second winding to adapt the electric phonograph for operation on power supply lines of different voltages, the various circuit elements of said electric phonograph being so apportioned between said first winding 35 and said second winding that fuse means of a single rating is adequate to protect all the elements of said phonograph circuit whether a power supply line is connected to one end or the other of said second winding.
- 40 8. An electric phonograph power supply for supplying power to a plurality of circuit elements of an electric phonograph, comprising, in combination, a transformer having a first and second winding and at least one other secondary winding having certain circuit elements connected thereacross, said first and second windings being adapted to be connected across an electrical power source to act as primaries and being adapted to 45 serve as secondary windings with respect to each other and to said secondary winding to supply electrical power to certain of said circuit elements connected across said first and second windings respectively, fuse means, said fuse means being connected in series between said first and second windings, means connecting one side of said power supply line with one end of said first winding, and means for connecting the other side of said power supply line to either end of said second winding to adapt the electric phonograph for operation on power supply lines of different voltages, the various circuit elements of said electric phonograph being so apportioned between said first winding 50 and said second winding that fuse means of a single rating is adequate to protect all the elements in said phonograph circuit whether a power supply line is connected to one end or the other of said second winding, relay means comprising energizing means and circuit control means, said circuit elements connected across said first or second windings including said relay energizing means, and said circuit control means of said relay being connected in a circuit 55 connecting certain other of said phonograph circuit elements directly to said power supply line whereby said latter elements are automatically disconnected from said power supply line when said fuse means operates.
